BED-DRIVING MECHANISM FOR POWER PLATE PRESSES

Application filed June 18, 1928. Serial No. 286,344.

The present invention relates to presses used in printing from flat engraved plates, and commonly known as power plate presses. In this class of machines the engraved plates are supported on beds which are moved about in a closed path on ways formed in a rectangular frame, so as to pass the plates successively under an inking roller, a wiping mechanism and an impression roller. The 10 beds carrying the plates follow a straight path along the sides of the frame and make a right angle turn at each corner. They are usually connected to a chain that is driven by sprockets at each of the four corners of the frame and it has been found that the action of this chain in passing around the sprockets causes an objectionable lateral motion of the straight portions of the chain which tends to deflect the bases from their normal path, especially 15 as they approach the turns. Guides have been used to steady the chain as it engages the sprockets but when they are placed in alignment with the sprocket teeth they do not extend close enough to the bottom of the 20 sprocket teeth to be effective, and when they are placed at one side of the sprocket teeth they engage the side links of the chain, which being of soft steel are rapidly worn. One member of the chain guide that is the subject 25 of the present invention avoids these difficulties, as will be hereinafter explained. Another member of the guide herein disclosed is shaped to conform with the outside of the chain as it passes around the sprockets and thus even should the chain be slack it will be held in close engagement with the sprockets and the beds kept in their proper path. Were 30 it not for this member a slackness in the chain would permit the beds to travel beyond their proper path in making the turns and strike against the side guides of the frame.

An object of the invention is to provide means for guiding the driving chain of a printing press of the type herein described so that when approaching and leaving the sprockets, the links of the chain will follow lines drawn tangent to the pitch lines of the sprockets and there will be no tendency to deflect the beds from their normal path.

Another object of the invention is to pro-

vide a chain guide that will hold the chain in close engagement with the sprockets when it passes around them.

Still another object of the invention is to provide an arrangement of chain, sprockets and chain guides for a machine of the type herein described, of generally improved construction, whereby the device will be simple, durable, inexpensive in construction and practical, serviceable and efficient in its use.

With the foregoing and other objects in view, which will appear as the description proceeds, the invention resides in the combination and arrangement of parts, and in the details of constructions hereinafter described and claimed, it being understood that various changes in the precise embodiment of the invention herein disclosed may be made within the scope of what is claimed, without departing from the spirit of the invention.

The invention has been illustrated in its preferred embodiments in the accompanying drawings, wherein:

Figure 1 is a plan view partly broken away showing one corner of a power plate press embodying the invention and illustrating one of the beds at the position where it begins to turn about the sprocket;

Figure 2 is a sectional view partly broken away showing the bed, frame, sprocket, chain and chain guide as viewed on the line A—A of Figure 1.

Figure 3 is a diagram showing the action of a chain when its sprocket is not provided with a chain guide such as is herein disclosed.

Referring to the drawing, this shows a corner portion of a frame work 11 that may be supported in any suitable manner. It will be understood that there are four such corners to the machine. The bushing 12 is fitted to the frame and forms a bearing for the shaft 13 on the end of which the double sprocket 14 is secured. The shaft is driven by means not shown and the sprocket engages the chain 15 which is thus caused to move along the four sides of the frame.

Ways 16 are formed in the frame and serve to support beds, one of which is indicated 17 and to which the engraved printing plate 18 is secured by any suitable means.

At suitable places in the chain 15, studs one of which is shown at 19, are inserted. This stud fits loosely in the bushing 20 which is secured to the bed 17. Side guideways 21 serve to confine the bed 17 although allowing it to move with the chain to which it is connected. By these means the bed is given a travelling movement around the frame and it carries the plate successively under inking, wiping and impression members not illustrated.

Referring to Figure 3, the circle 14' indicates the sprocket 14 with the teeth omitted for clearness. The chain 15 is shown in solid lines in the position it would occupy when a pin in the chain is engaging the sprocket at the point P. Portions of the chain are also shown in dotted lines in the positions they would occupy when a pin in the chain is engaging the sprocket at the point P'. It will thus be seen that as the chain passes around the sprocket the pins of the chain will be at 15 and the center line of the chain at 15' when it engages the sprocket at P, and the 25 pins will be at 115 and the center line of the chain at 115' when it engages the sprocket at P'. Inasmuch as the beds are connected to the chain it will be understood that any sidewise movement of the chain would tend to 30 deflect the beds from a straight course and out of engagement with the side guides at those points where they are guided on but one side.

Guides have been used heretofore as shown in Halliwell Patent No. 1,619,820 to keep the 35 chain on a line tangent to the pitch line of the sprocket as the sprocket is approached but owing to their constructions they could not be made to support the chain close enough to the sprocket to prevent sidewise motion 40 of the chain just before it engages the sprocket. A further objection to such chain guides is that they bear against the side links of the chain which are not hardened and consequently are rapidly worn. The invention herein 45 disclosed provides means for guiding the chain so that it approaches the sprocket on a line that is tangent to the pitch line of the sprocket at all times, and the chain is engaged on its centre members which are made of hardened steel and are thus protected from 50 wear.

The member 22 of the chain guide is fastened to the frame 11 by screws 23 and is formed to occupy the space in the groove of 55 the sprocket, passing partly around it and the other end being fastened to the bed 11, by the screws 24. It will be understood that by thus guiding the chain on the inside or sprocket side, it is held in a path corresponding to the line 15' of Figure 3 and that the 60 beds are moved forward in the proper path.

Should the chain slacken the momentum of the beds would tend to carry them too far when they make the turns and allow them 65 to strike the side guides unless means is pro-

vided to hold the chain in close engagement with the sprocket. The member 25 of the chain guide is secured to the frame 11 by the screws 26 and being shaped to conform to the outside of the chain as it passes around the sprockets constitutes an effective means of preventing any over travel of the beds.

It will be seen that an effective means is provided for guiding the chain so that the studs 19 are caused to follow a path corresponding to the pitch line of the sprockets and tangent thereto, and that the beds will not be deflected from their path by any side motion of the chain nor allowed to swerve from their true course by any slackness thereof.

What we claim is:

1. In a plate printing machine, a frame, a bed, a chain connected to the bed, a sprocket engaging the chain, and a guide member engaging the centre members of the chain and on the inside thereof to keep it in a path tangent to the pitch line of the sprocket as it engages therewith. 85
  2. In a plate printing machine, a frame, a bed, a chain connected to the bed, a sprocket engaging the chain and having teeth in a plurality of separate axial planes, and a guide member between the separate planes and engaging the chain to keep it in a path tangent to the pitch line of the sprocket as it engages therewith. 95
  3. In a plate printing machine, a frame, a bed, a chain connected to the bed, a sprocket engaging the chain, and a guide member outside the path of the chain and formed to hold the chain in close engagement with the sprocket. 100
  4. In a plate printing machine, a frame, a bed, a chain connected to the bed, a sprocket engaging the chain and a chain guide having members engaging the inside of the chain to keep it in a path tangent to the pitch line of the sprocket as it engages the sprocket and a member engaging the outside of the chain to hold it in close engagement with the sprocket. 105
  5. In a plate printing machine, a frame, a bed, a chain connected to the bed, a sprocket engaging the chain, and guide members adjacent to the sprocket and between which the chain passes and is guided to, and around the sprocket. 115
  6. In a plate printing machine, a frame, a bed, a chain connected to the bed, a sprocket engaging the chain, and guide members arranged to act on the inside and outside of the chain where it moves in a curved path. 120
